(57) **CLAIM**

The ornamental design for an adjustable height trailer connector, as shown and described.

DESCRIPTION

FIG. 1 is a front, left and top perspective view of an adjustable height trailer connector, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1; and,

FIG. 10 is a partial enlarged view of an area labeled 10 in FIG. 2.

The broken lines depict portions of the adjustable height trailer connector that form no part of the claimed design. The dot-dash broken lines in FIGS. 1, 2, 9 and 10 depict the boundaries of the enlargements that form no part of the claimed design.

1 Claim, 10 Drawing Sheets
